UNITED STATES PATENT OFFICE.

SAM G. LANGLEY, OF MAPLEWOOD, NEW JERSEY, ASSIGNOR TO NEW JERSEY PATENT COMPANY, OF WEST ORANGE, NEW JERSEY, A CORPORATION OF NEW JERSEY.

SWITCH.

1,323,194.

Specification of Letters Patent. Patented Nov. 25, 1919.

Original application filed June 18, 1912, Serial No. 704,338. Divided and this application filed December 13, 1916. Serial No. 136,782.

To all whom it may concern:

Be it known that I, SAM G. LANGLEY, a citizen of the United States, and a resident of Maplewood, in the county of Essex and State of New Jersey, have invented certain new and useful Improvements in Switches, of which the following is a description.

My invention relates to switches and more particularly to an improved automatic switch which is especially adapted for controlling circuits carrying heavy currents, this application being a division of my application Serial No. 704,338, filed June 18, 1912, entitled Means for charging storage batteries, which has resulted in Patent No. 1,215,309, dated February 6, 1917.

The principal object of my invention is to provide a simple and efficient switch of this type, which comprises few parts and which is positive in its action to effect the making and breaking of the circuit controlled thereby.

My invention also includes the combinations of elements and details of construction hereinafter more fully described and claimed.

For a clearer understanding of my invention, attention is directed to the drawing accompanying and forming part of this specification, and in which:

Figure 1 is a side elevation of my improved automatic switch with the contacts closed;

Fig. 2 is a plan view of the same with the contacts open;

Fig. 3 is a vertical view at right angles to the view of Fig. 1; and

Fig. 4 is a horizontal sectional view on the line 4—4 of Fig. 3.

Referring to the drawing, reference character 10 represents a supporting member which may be made of a single piece of sheet metal and which has a horizontal portion 11 and upwardly extending vertical portions 12 and 13. The supporting member 10 supports the parts of my improved automatic switch and may be secured to any suitable base member 15. If the base member is of conducting material, the supporting member 10 is preferably insulated therefrom, but if the base member is of insulating material other insulating means are

not necessary in securing the supporting member 10 to the base member 15.

On the upwardly extending vertical portion 13 of the supporting member 10 horizontal electro-magnets are mounted, the said electro-magnets comprising magnetic cores 24 and 25, one end of each core being secured to the portion 13 in any suitable manner, as for example, by screws, the core 24 having a winding 26 surrounding it and insulated therefrom, and the core 25 having a winding 27 surrounding it and insulated therefrom. The ends of the cores 24 and 25 which are farthest from the portion 13 are provided with projecting pins of non-magnetic material constituting guides for an armature 30 of soft iron which is elongated in form and has openings near its ends to receive the guides 28 and 29. The armature 30 is provided with a member 31 preferably of non-magnetic material secured at right angles thereto and extending horizontally through an opening 32 in the upright portion 13, the said upright portion 13 thereby constituting a guide for the member 31. On the portion of the member 31 which extends through the upright portion 13 a collar 33 or other suitable means is provided for limiting the movement of the armature 30 away from the cores 24 and 25 of the electro-magnets.

On the upwardly extending portion 12 of the supporting member 10 a contact 34 is mounted and suitably insulated therefrom. The contact surface of this contact faces the end of the member 31 which extends through the opening 32 on the upwardly extending vertical portion 13. The contact 34 is preferably a metallic disk or block and is provided with a reduced portion 57 extending through an opening in the upright portion 12, and with a threaded stem 97. The threaded stem is provided with a nut 35 which co-operates with the disk or block 34 and with insulating washers to hold the contact in place on its support, and with washers 36 and a nut 35' which afford means for connecting the contact 34 in circuit with a conductor 93. On the upright portion 12 is also mounted a spring contact 37 which consists of an elongated portion and end portions 39 and 38

bent back approximately parallel to the elongated portion when the contact is in closed position. The portion 38 of the spring contact 37 is secured to the upwardly extending vertical portion 12 by any suitable means, as for example, a bolt and nut 40. At the end of the portion 38 an inturned projection 42 is provided which co-operates with a slot 41 in the upright portion 12 to position the contact against rotary displacement around the bolt 40. The head of the bolt 40 co-operates with a washer to connect the contact in circuit with a conductor 67, the latter being in circuit with conductor 93. The end 15 of the portion 39 of the spring contact 37 is split into a plurality of parts or fingers which constitute contact faces co-operating with the contact 34, and insure adequate contact therewith. On account of the resiliency 20 of the spring contact 37, the portions 38 and 39 tend to spring out of parallelism with the elongated portion of the spring, and thereby move portion 39 away from the contact 34 as illustrated in Fig. 4. When, however, the windings 26 and 27 are energized, the armature 30 is attracted toward the cores 24 and 25, and the contacts 37 and 34 are forced into closed position by the end of the member 31. It is to be observed that the 25 entire length of the spring contact 37, including the bent back portion 39, is effective in exerting pressure against the actuating member 31, and that, on account of the shape of the spring, this pressure is great 30 when the armature 30 is in contact with or nearest the cores 24 and 25. The bent back portion 39 contributes materially to forcing the armature 30 away from the cores, which 35 effectually overcomes any tendency of the armature to stick to the cores.

When the magnet windings 26 and 27 are energized, the armature 30 is attracted to the cores 24 and 25, contacts 37 and 34 are closed by the action of the member 31 secured to the armature 30, and the circuit through conductors 67 and 93 is closed. Upon breaking the circuit through the magnet windings 26 and 27, the resiliency of the spring contact 37 forces the armature 30 away from its core and separates contact 37 from contact 34, thereby breaking the circuit through conductors 67 and 93.

While I have described the preferred embodiment of my invention, it is to be understood that various changes may be made in the size, form and arrangement of its parts without departing from the spirit of the invention and the scope of the appended claims.

Having now described my invention, what I claim and desire to protect by Letters Patent is as follows:—

1. In apparatus of the class described, a

contact, and a spring contact member having a turned over end portion adapted to be 65 engaged with said contact by flexing said member, said end portion being split to form a flexible contact face and being biased by said member to a position in which it is out of engagement with said contact, substantially 70 as described.

2. In apparatus of the class described, a supporting member, a pair of electro-magnets supported horizontally thereon, an armature for the electro-magnets, guiding 75 means for the armature, a fixed contact, a movable contact unattached to said armature and co-operating with said fixed contact, said movable contact being normally biased out of circuit closing position, and a horizontally disposed extension on the armature adapted to engage the movable contact and force it into circuit closing position when the electro-magnets are energized, substantially 80 as described.

3. In apparatus of the class described, the combination of a stationary contact, a spring contact mounted to co-operate therewith and normally biased out of contact therewith, a member located to engage said spring contact to move it into circuit closing position and including an armature, an electro-magnet for moving said member into contact engaging position, substantially 85 as described.

4. In apparatus of the class described, an electro-magnet, an armature for the electro-magnet, guiding means for the armature applied to the core of the electro-magnet, a fixed contact, a movable contact unattached to said armature and co-operating with said 90 fixed contact, said movable contact being normally biased out of circuit closing position, and an extension on the armature adapted to engage the movable contact and force it into circuit closing position when 95 the electro-magnet is energized, substantially as described.

5. In apparatus of the class described, a stationary contact, a spring contact mounted to co-operate with said stationary contact 100 and normally biased out of contact therewith, a member located to engage said spring contact to move it into circuit closing position and including an armature, and an electromagnet for moving said member into 105 contact engaging position, said member being biased by said spring contact to a position in which the armature is in spaced relation to the core of said electromagnet, substantially as described.

This specification signed and witnessed this 12th day of December, 1916.

SAM G. LANGLEY.
